United States Patent Office

Des. 176,749
Patented Jan. 31, 1956

176,749

SPOON OR SIMILAR ARTICLE

John Brokate, Wallingford, Conn., assignor to Utica Cutlery Company, Inc., Utica, N. Y., a corporation of New York

Application January 28, 1955, Serial No. 34,273

Term of patent 14 years

(Cl. D54—12)

FIG. 5

Fig. 1 is a front elevation of a spoon or similar article embodying my new design;

Fig. 2 is a side elevation of the same;

Fig. 3 is a section taken along the line 3—3 of Fig. 1 in the direction of the arrows;

Fig. 4 is a section taken along the line 4—4 of Fig. 1 in the direction of the arrows; and

Fig. 5 is an enlarged view of the handle element of the spoon, as shown in Fig. 1.

The back of the spoon is plain.

I claim:

The ornamental design for a spoon or similar article, substantially as shown and described.
